UNITED STATES PATENT OFFICE.

JOHN WILLIAM WEISEISEN, OF HIGH POINT, NEW JERSEY.

DESIGN FOR A DOOR KNOCKER.

Application filed October 1, 1925. Serial No. 14,985. Term of patent 14 years.

To all whom it may concern:

Be it known that I, JOHN WILLIAM WEISEISEN, a citizen of the United States, residing at High Point, in the county of Ocean and State of New Jersey, have invented a new, original, and ornamental Design for a Door Knocker, of which the following is a specification, reference being had to the accompanying drawing, forming part thereof.

Figure 1, is a front elevation of a door knocker.

Figure 2, is an edge view thereof.

Figure 3, is a section at the line 3—3 of Fig. 1.

I claim—

The ornamental design for a door knocker, as shown.

JOHN WILLIAM WEISEISEN.
